DESIGN FOR A HANDBAG

Louis Carl Levine, Brooklyn, N. Y.

Application August 30, 1943, Serial No. 111,028

Term of patent 7 years

To all whom it may concern:

Be it known that I, Louis Carl Levine, a citizen of the United States, residing in Brooklyn, in the county of Kings and State of New York, have invented a new, original, and ornamental Design for a Handbag, of which the following is a specification, reference being had to the accompanying drawing, forming part thereof.

Fig. 1 is a front elevational view of a handbag showing my design.

Fig. 2 is the rear elevational view thereof.

Fig. 3 is a perspective view of the handbag in opened position and,

Fig. 4 is an edge view of the handle member of the bag, illustrating the surface trim detail of the handbag.

The characteristic features of my design reside in the portions shown in full lines on the drawing.

I claim:

The ornamental design for a handbag, substantially as shown and described.

LOUIS CARL LEVINE.
